Feb. 5, 1924.

1,482,928

F. HUTTER

COVER FOR MAGAZINES AND THE LIKE

Filed June 23, 1920

Fig. 1.

Fig. 2.

FRANZ HUTTER
Anthony J. Lanza
ATTORNEY

UNITED STATES PATENT OFFICE.

FRANZ HUTTER, OF NEW YORK, N. Y., ASSIGNOR TO THE McCALL COMPANY, A CORPORATION OF NEW YORK.

COVER FOR MAGAZINES AND THE LIKE.

Application filed June 23, 1920. Serial No. 390,990.

To all whom it may concern:

Be it known that I, FRANZ HUTTER, formerly a subject of the Emperor of Austria-Hungary, having declared my intention 5 of becoming a citizen of the United States, residing in the city, county, and State of New York, have invented certain new and useful Improvements in Covers for Magazines and the like, of which the following is 10 a specification.

My invention aims to provide a cover or outside sheet for magazines, periodicals, circulars and similar printed matters sent at intervals to subscribers whereby certain 15 serious disadvantages in the distribution thereof are eliminated.

The accompanying drawings illustrate the application of the invention to the front cover of a monthly magazine; Fig. 1 being a 20 view of the upper part of a sheet, and Fig. 2 an enlarged view of the upper right hand corner of the same sheet.

Great difficulty is experienced by publishers in getting prompt information from subscribers of changes of their address and of 25 renewals of their subscriptions, generally through the failure of the subscribers to give the proper notices in due time. The result is that publishers of magazines of large 30 circulation, have practically every month to send out extra copies which subscribers have failed to receive through such neglect. The publisher is put to extra expense and the subscriber is sometimes dissatisfied at not 35 receiving his copies promptly. Various expedients have been adopted to call the subscriber's attention to the date of expiration of his subscription and to the need of 40 promptness on his part in renewing it. My invention provides an arrangement whereby a direct personal appeal is made to the subscriber by or in close association with his individual name, which arrangement may be utilized for any or all of a number of different 45 sorts of notice or appeal to the subscriber, and may also be used as a conspicuous coupon to be used by the subscriber in various ways. By this arrangement the address or the space provided therefor is made 50 to serve additional functions besides that of ensuring the correct delivery of the magazines, and these additional functions are of great value in maintaining and increasing circulation of the magazine and in saving 55 incidental expenses, as hereinafter referred to in detail.

Referring to the case illustrated, the cover is printed with a distinct, conspicuous, blank space along the right hand edge entirely outside of the usual printed matter, and this 60 space is balanced by a similar one on the left hand side, both being near the upper edge.

I have assumed that the main part of the cover is printed in colors or on a colored field A with a margin B of white around it, 65 in which case the corner spaces C and D may be white and merged in the margin. The space C may be utilized for advertising one or more special features and is located so as to make such advertisement conspicuous, and also to balance the space D and make an attractive and symmetrical cover. For example, in the space C we may print 70 "Vincente Blasco Ibanez, A Shot in the Night, see page 6."

The space D is shown on an enlarged scale in Fig. 2. On the right of it, is a space E which will be left blank, the balance of the cover being printed uniformly for all copies. The balance of the space D is indicated at F and the matter printed therein is the same for all copies. The entire space D is preferably enclosed within a line as indicated so that it may be cut off and used as a coupon for a purpose hereinafter stated. 85 The space E may also be outlined as indicated in dotted lines, but it is not essential either that the whole space D or the smaller space E be outlined. And, though I consider it important for the best results that 90 the spaces E and F be directly adjoined to each other, yet this is not essential as long as they are in such near relation that the subscriber, his eye caught by his name printed usually in stencil or other distinctive 95 type and on a conspicuous blank space, will also see the notice directed to him and referring particularly to the address.

Within the space E three smaller spaces are indicated. These may be of various arrangements and dimensions. The space G will contain the subscriber's name and address. As for example, "Richard Roe, 100 Broadway, New York City." The space H will contain the date of expiration of his 100 subscription as for example, "July 1920", meaning that the July 1920 number of the magazine is the last one which he is entitled to. The third space J is left for a special expiration notice. An address and date of expiration will be stencilled or otherwise printed on each number. The "expired" notice, however, will be printed only on the last number due to the subscriber to whom it is addressed.

The above description assumes that the magazine is sold only to subscribers. Where it is sold in individual numbers to the public, as on news stands, or in shops, the space E will be left blank and this conspicuous blank space will be put to another use, specified below.

15 The space F may be used for various appeals to the purchaser and in the case of a subscriber becomes practically a personal letter addressed to him. I have shown on the drawing a notice covering four particular points, but the number may be increased or decreased and the character of the matters covered may be varied according to circumstances and the publisher's preference.

25 The first notice relates to the address of the subscriber and warns him to give sufficient notice of any desired change. Failure of such notice from a subscriber is a frequent cause of expense and loss to the publisher and annoyance to the subscriber. And 30 the use of this direct personal appeal will greatly diminish such expense and annoyance.

35 The second notice calls attention to the expiration date also printed in the adjoining space and thus gives the subscriber each month a direct personal warning of the length of time which his subscription has still to run. This direct personal appeal will also save considerable expense and annoyance and will help materially to increase the number of subscribers who renew their subscription, which is of the utmost importance.

40 The third notice indicates the fact that this is the last copy which the subscriber will receive unless he renews. In connection with this, the "expired" notice J is stamped or printed in the adjoining space. This may comprise, for example, the words "Subscription Expired", or a mark in distinctive color, or any other conspicuous direction. The warning emphasizes this. Being printed on each copy of the magazine it also serves the subscriber with information that he will get 55 such a notice of expiration unless he renews in time, which is much preferable.

60 The fourth paragraph of the notice is directed to non-subscribers and is located adjacent to the space E which, in such a case, is a conspicuous blank space, or provided with dotted lines on which the purchaser can write his address. This blank space with the adjacent printed notice serves the purpose of a conspicuous subscription coupon at a point 65 where it can seldom fail to attract the attention of the purchaser; namely, on the cover and preferably on the most conspicuous part of the cover, the upper right hand corner. This location is particularly advantageous, not only for a coupon intended for non-subscribers, but also for subscribers' use. On the counters of news stands and shops and also on the tables of public and private libraries it is common to stack magazines with the lower part of each magazine covered by the next one, leaving the upper part exposed; and under these circumstances it is particularly advantageous to arrange the features of my improvement at the top of the page.

70 The provisions described are not necessarily limited to the front page of the front cover, although they are particularly advantageous in this location. They may be applied with considerable advantage to the 75 rear page of the back cover or to various outer sheets, wrappers and so forth which are sometimes used in the distributing of magazines and the like; all of which I include in the term "magazine cover."

80 The several notices to be used in connection with the address or coupon may be printed in type similar to that used for the address and of corresponding color so as to make the connection more noticeable. Also 85 the formal title, such as "Notice to Subscriber" may be omitted and the stencils or other devices used for printing the address may carry also the name of the subscriber, as "Dear Mr. Roe" in such a position that it 90 will appear at the head of the printed matter which is common to all copies. Also this printed matter may be on lines parallel with the lines of the address instead of at an angle thereto as in the drawing. In fact 95 the user of the invention may arrange the address and the common printed matter in any one of various ways with relation to each other.

100 The character of the magazine will influence the character of the common printed matter and the use or uses to which the address coupon is put. For example, this coupon, with the subscribers address thereon may be used as a receipt for subscriptions, 105 to which value may be attached according to various schemes. It may constitute the whole or part of an accident insurance premium, such as magazines have some times offered to subscribers. It may identify the 110 subscriber as entitled to certain privileges announced in the advertising pages of the magazine. And whatever value may be attached to it or whatever use may be made 115 of it will be set forth in the common printed matter which is directed particularly to the individual subscriber.

120 Some addressing machines print the addresses on separate slips and paste them on the cover. This system may also be used 125 with my invention, merely pasting the slip on the space provided therefor and in proper relation to the common printed matter.

The advantages of the invention are numerous and valuable. The application of the address to the outer page of the cover has been generally regarded as spoiling the beauty or artistic effect of the cover and serving only as an economical way of ensuring correct delivery and as forming a reminder for the publisher alone of the expiration date. By providing a separate independent space for it entirely outside of the rest of the cover it has less effect on the artistic appeal of the latter. By using it practically as the heading of a personal letter to the individual subscriber it has a valuable psychological effect in attaching him to the magazine. And by combining it with the common printed matter it is made to serve one or more of a number of new functions and to provide a thing of utility to the subscriber and of great value to the publisher instead of a mere disfigurement. It reduces to the simplest possible operation the subscriber's work in changing or correcting his address, renewing the subscription, sending in a new subscription or identifying himself as a subscriber.

Though I have described with great particularity of detail a certain specific embodiment of my invention, yet it is not to be understood that the invention is restricted to the particular form shown. Various modifications thereof in detail and in the arrangement of the parts may be made by those skilled in the art without departure from the invention as defined in the following claims.

40 What I claim is:

1. A magazine cover having a delineated portion adapted to be used as an order for subscription and showing on its outer face an indicated space distinct from and entirely outside of the remainder of the cover, the said indicated space adapted to carry the address of the individual subscribers and an adjoining space carrying a notice common to all copies and directing the attention of the purchaser to the use to which 50 said delineated portion may be put.

2. A magazine cover having a delineated portion adapted to be used as an order for subscription and showing on its outer face an indicated space for the name and address 55 and date of expiration of subscription for individual subscribers and an adjoining space carrying a printed notice directed to the said subscriber and calling his attention to the date on which his subscription 60 will expire and to the use to which said delineated portion may be put.

3. A magazine cover having a delineated portion adapted to be used as an order for subscription and showing on its outer face 65 an indicated space for the address of the individual subscribers and for a notice that his subscription has expired and having an adjoining space carrying a printed notice calling his attention to the fact that the 70 last copy of his subscription will contain such a notice of expiration and to the use to which said delineated portion may be put.

4. A magazine cover having a delineated 75 portion adapted to be used as an order for subscription and showing on its outer face an indicated space adapted to carry the address of the individual subscribers or to be left blank on copies which are sold to 80 non-subscribers and having an adjoining space carrying a printed notice to non-subscribers that the delineated portion of the cover may be used as a coupon for ordering a subscription by writing the subscriber's 85 name and address thereon.

5. A magazine cover having on its outer face an indicated space constituting an address coupon and adapted to carry the name and address of the individual subscribers 90 and an adjoining space carrying a notice common to all copies and directing attention to said address coupon.

In testimony whereof, I have hereunto signed my name.

FRANZ HUTTER.